UNITED STATES PATENT OFFICE

125,099

DESIGN FOR AN END COVE PIECE OR SIMILAR ARTICLE

William L. Bonnell, Columbus, Ohio

Application October 27, 1939, Serial No. 87,899

Term of patent 14 years

To all whom it may concern:

Be it known that I, William L. Bonnell, a citizen of the United States, residing at Columbus, in the county of Franklin and State of Ohio, have invented a new, original, and ornamental Design for an End Cove Piece or Similar Article, of which the following is a specification, reference being had to the accompanying drawing, forming a part thereof.

Fig. 1 is a perspective view looking toward the

outer end of an end cove piece or similar article showing my new design;

Fig. 2 is a perspective view looking toward the inner end;

Fig. 3 is a plan view;

Fig. 4 is a horizontal sectional view thereof.

I claim:

The ornamental design for an end cove piece or similar article, as shown.

WILLIAM L. BONNELL.
